NO. 7766

12/2/1974

UNITED STATES PATENT OFFICE.

FLORENCE KROEBER, OF HOBOKEN, NEW JERSEY.

DESIGN FOR CLOCK-CASES.

Specification forming part of Design No. 7,766, dated September 22, 1874; application filed August 15, 1874.
[Term of Patent 3½ years.]

CASE A.

To all whom it may concern :

Be it known that I, FLORENCE KROEBER, of Hoboken, in the county of Hudson and State of New Jersey, have invented a new and original Design for Clocks, of which the following is a specification:

The drawing represents a front elevation of my new design for clocks.

This invention relates to a new design for a clock; and consists, first, in arranging a thermometer at the side of the dial; and, secondly, in the general configuration of the clock-case.

In the drawing, the letter A represents the case or frame of a standing clock. B is the dial of the same. C is a thermometer applied to the face of the frame at one side of the dial. By having the thermometer at the side of

the dial the entire design receives a peculiar character, as the clock is made lower and broader than it could be made if the thermometer were under or above the dial. The case or frame A is made in form of a cottage, with gable roof, and with an imitation door, D, at the side opposite to the thermometer, as shown.

I claim as my invention—

1. The design for a clock having a thermometer at one side of the dial, as shown.
2. The design for the cottage-shaped clock-case A, having the door B at one side of the dial, as shown.

F. KROEBER.
